M. A. KING, OF NEW YORK, N. Y.

Letters Patent No. 77,051, dated April 21, 1868.

IMPROVEMENT IN MUFFS.

The Schedule referred to in these Letters Patent and making part of the same.

TO ALL WHOM IT MAY CONCERN:

Be it known that I, M. A. KING, of the city of New York, in the State of New York, have invented a certain new and useful Improvement on Muffs; and I do hereby declare that the following is a full, clear, and exact description thereof, reference being had to the accompanying drawings, and to the letters and marks thereon, which said drawings form part of this specification, and represent a muff, and the frame thereof, as constructed under my invention—

Figure 1 being a view of the frame, and

Figure 2 a view of the muff.

In both of these figures like parts are indicated by like marks and letters.

This invention is of the character of an additional improvement to a muff, on which Letters Patent were granted to me on the 10th day of December, 1867; the muff having a frame between its exterior and interior surfaces, similar to that shown by fig. 1, without the continuation marked *a*, of the central spring-bar or strip; a hinged section of the frame being for a lid or cover to a reticule or pocket lying between the fur or exterior surface of the muff, and the lining and wadding or interior surface. As this frame, whether made of metal-spring strips or light bars, must necessarily be of little weight, the hinges, without some sustaining means, will be liable to be strained or broken by careless raising of the lid or cover, and the catch of the lid will not be likely to fit as accurately and safely in its socket in the front bar of the reticule.

In raising the lid or cover *b* of the reticule *c*, if pressed too far back, the hinges might be strained or broken, and when so pressed back the contents of the reticule would be much exposed to observation.

My present improvement consists in having the central bar or strip *a* pass through the bar *d* of the lid, and the bar *e* of the frame. This strip is secured to the bar *e*, as indicated at *f*, fig. 1, but is not secured to the bar *d*, a slot in that bar allowing of the moving of the lid up or down to open or close the reticule. This strip or spring plate *a* will prevent the lid from going too far back, will sustain the hinges and prevent their being strained or broken, and will direct or guide the catch to its socket, so that the reticule can be opened and closed as easily and readily in the dark as in the light.

What I claim as my invention, and desire to secure by Letters Patent, is—

The spring strip *a*, in combination with the other parts of the frame and muff, substantially as and for the purposes set forth.

This specification signed this 18th day of March 1868.

M. A. KING.
